UNITED STATES PATENT OFFICE

2,082,217

WRINGER

Julian L. Perkins, West Springfield, Mass., assignor to Perkins Machine & Gear Company, West Springfield, Mass., a corporation of Massachusetts

Application October 22, 1934, Serial No. 749,378

7 Claims. (Cl. 68—32)

This invention relates to improvements in wringers, more particularly of the type shown in United States Letters Patent Nos. 1,902,580, 1,906,406 and 1,906,407.

5 The principal objects of the invention are directed to improvements in wringers of the type shown in the patents referred to wherein means is provided to guard against clothes being wound around a wringer roll and novel means is provided which is adapted to serve as a drain-board while the wringer is in operation and to conceal the rolls when the wringer is not in operation, thereby to provide a pleasing appearance as well as to protect the rolls.

15 Various other novel features and advantages of the invention will be hereinafter more fully referred to in connection with the accompanying description of the present preferred form of the invention, reference being had to the accompanying drawings wherein:

20 Fig. 1 is a combined longitudinal sectional and side elevational view of a wringer embodying the novel features of my invention;

Fig. 2 is a fragmentary sectional view through 25 the ends of the guard plates of the wringer shown in Fig. 1;

Fig. 3 is a perspective view of the end portions of the guard plates;

Fig. 4 is a sectional elevational view on the line 30 4—4 of Fig. 1;

Fig. 5 is a sectional plan view on the line 5—5 of Fig. 4;

Fig. 6 is a sectional elevational view similar to Fig. 4 on the line 6—6 of Fig. 1 with certain of 35 the parts in section for clearness;

Fig. 7 is an enlarged sectional plan view on the line 7—7 of Fig. 1;

Fig. 8 is a sectional view on the line 8—8 of Fig. 6;

40 Fig. 9 is a perspective view of one of the receivers;

Figs. 10 and 11 are sectional views on the line 10—10 of Fig. 1 with the parts shown in different positions; and

45 Fig. 12 is a perspective view of a yoke member.

Referring now to the drawings more in detail the invention will be fully described.

The novel features of the invention are adapted for broad application but are particularly 50 adapted for use in connection with a wringer for a washing machine where material is received by the wringer from a washing machine tub. The head of the wringer is represented by 1 and may include a frame or housing and a column 2 55 as shown which is arranged for mounting on the

upper side of the usual column of a washing machine. The usual wringer driving element or pinion which is driven by the washing machine mechanism is represented by 4.

The frame 6 associated with the head has a 5 hub 8 in which is rotatable a driven shaft 10. The inner end 12 of the said shaft 10 is rotatable in a hub part 14 at the forward end of the head frame which is hollowed out to receive an end portion 16 of a shaft 18 of a lower drive roll 20. 10 A pin 21 of shaft part 16 is received in a slot of the end 12 of shaft 10 whereby the shafts are operatively connected.

A shiftable member 22 has an end bearing 24 which is slidable and oscillatable on the bearing 15 8 of frame 6. A forward portion 26 of member 22 is oscillatable and slidable on shaft 10. This member 22 by being reciprocable back and forth on shaft 10 moves gears 28 on shaft 10 back and forth to bring them into and out of mesh with 20 the pinion 4. A key or keys 27 associated with one gear 28 and shaft 10 permits the gears to slide on the shaft but serves for driving the gears from the shaft, the said gears being connected to a tubular member 29 as by welding so that 25 they move simultaneously.

A stud member 30 associated with frame 6 has a lower end 32 in engagement with an angularly-disposed slot 34 of member 22 as shown in Figs. 1 and 7. This is so that as the member 22 is 30 oscillated relative to shaft 10 it will be reciprocated to move the gears 28 relative to pinion 4.

A yoke member 40 is oscillatable on the hub portion 14 of the head and is provided with a slot 42 in its upper side as shown in Fig. 12. A lug 35 23 of member 22 carries a roll 44 which extends through an opening 7 at the inner side of frame 6 (see Fig. 4). This roll 44 is disposed between ribs 46 associated with the yoke 40 at its rear side. As the yoke 40 is oscillated, the member 22 40 is oscillated thereby and simultaneously moved back and forth to bring the gears 28 into and out of engagement with the pinion 4.

A receiver 50 is slidable up and down in the head which has a vertically extending slot 52 on the inner face thereof as shown in Figs. 4, 6 and 9. The said slot 52 is widened out below its upper end as at 54 and rolls 56 in slots such as 57 are pivoted at 58 so their adjacent peripheries extend inwardly from the sides of the slot 54. Projections 60 also extend from the sides of the slot 54 as shown. A cap 62 is pivoted at 64 to the receiver and is arranged so that it overlies slot 55 50 and may swing upwardly from the position

shown in Fig. 6 from off the upper end of the slot 52 to the position shown in Fig. 4.

There is an ear such as 66 on either side of the receiver, as shown in Figs. 4 and 9, and webs 9 extend across the frame 6. Bolts such as 68 are associated with the ears of the receiver and are slidably mounted in the web 9.

A spring 70 is provided around each bolt to urge the receiver downwardly. Longitudinal side webs 80 extend from the frame 6, and are connected to an outer end frame 82. The frame 6, webs 80 and outer frame 82 constitute a wringer frame or support. The outer frame 82 has a receiver slidably mounted therein similarly to that described in connection with the head end of the wringer and a cap 62 is provided on the receiver associated with frame 82. The receivers receive opposite ends of an upper roll-guard or separate frame assembly unit G after the manner disclosed in the above-mentioned patents. It will be understood that the receiver associated with frame 82 moves up and down as does the receiver in frame 6 and, being similarly mounted, they are both urged downwardly by springs.

25 The outer end 11 of shaft 18 of lower roll 20 is journalled for rotation in the outer end frame 82 as shown in Fig. 1.

The roll-guard assembly is indicated by G and includes a manually engageable longitudinally extending frame guard bar 90 which has lugs such as 92 depending from opposite ends thereof (see Fig. 1). Hubs 94 are associated with the lugs 92 and an upper roll 96 and shaft 98 are associated with the hubs so that the said roll is freely rotatable relative to the guard bar. Projections such as 98 extending outwardly are associated with the hubs 94 at opposite ends of the frame or guard.

The frame or guard unit may be inserted with 40 in the wringer or withdrawn therefrom. As it is inserted in the wringer the hub 94 at the head end of the frame enters the slot 42 of yoke 40 while the projections 98 at opposite sides enter the slots 52 of the receivers associated with the frame 6 and frame member 82. As the roll frame or guard is inserted in the wringer, the yoke 40 is in a neutral position, with the slot uppermost to receive hub 94. When the roll guard has been inserted in the receiver slots with roll 96 resting 45 on roll 20 the operator swings the guard to one side or the other so that the projections 98 engage beneath one of the rolls 56 of the receivers while the hubs 94 are disposed beneath one of the projections 60 in the receiver slot to releasably 50 lock the roll unit in one operative position. As the guard is swung the yoke 40 is swung thereby to oscillate member 22 and cause one of the gears to engage with the pinion 4. The frame unit is shown in one operative position in Figs. 6 and 11. 55 In such a position as shown in Fig. 6 the projections 60 lie under rolls 56 while the hubs 94 lie under projections 60 of the receivers. With the upper roll resting on the lower roll the frame is releasably locked to the wringer. As material 60 is passed through the rolls the upper one is elevated and it elevates the receivers which are spring pressed downwardly. In this way the upper roll is under the influence of springs 70.

Depending upon the direction in which the 70 frame 90 is swung to an operative position, the rolls 20 and 96 will be driven in one direction or the other. It is desired, however, that the rolls be so driven that the leading-in side thereof is at the side of the wringer on which the guard is located when in operative position.

In Figs. 6 and 11 the leading-in side would be the left-hand side, the frame or guard being located on that side of the wringer. The general construction of the wringer thus far described and its mode of operation is similar to that disclosed in the patents above referred to and need not be described herein more in detail.

Guard plates 100 extend along the bar 90 and carry hubs 101 on their opposite ends which are pivoted as on a rod or rods such as 102 which is 10 associated with the bar 90. As shown in Fig. 2, a spring 104 has its opposite ends in engagement with the hubs 101 of the members 100. This is arranged to cause the plates to swing downwardly and inwardly so that their lower ends will 15 yieldingly bear along the sides of the upper roll 96.

Longitudinally extending cover and drain plates 110 are pivoted at 112 adjacent their lower sides and opposite ends to inner sides of the 20 frame 6 and frame member 82 so that they may swing between the positions shown in Figs. 10 and 11. In their upper position such as shown in Fig. 10 they overlie the sides of the rolls 20 and 96 and the longitudinal lower edges of the guard 25 plates 100 overlie their upper edges as shown to hold them in position.

When the members 110 are in their upper position shown in Fig. 10, they conceal the rolls from end to end of the wringer and not only 30 protect the rolls but present a pleasing appearance. When in their lower position such as shown in Figs. 4 and 11, they serve as drain boards. When the wringer is to be operated, the members 110 are released by swinging the members 100 upwardly so that said members 110 may swing to their lower position.

Locks 120, more clearly shown in Figs. 6 and 8, are pivoted as at 122 to ears 123 of the frame 6 and have finger engaging portions 124 which extend downwardly below the frame. Projecting parts 126 extend forwardly from the frame through slots 121 engage upstanding flanges 111 of the members 110 to lock the members 110 in the inclined position shown in Figs. 6 and 11. 45 When the locks release the members 110, they may be swung to their upper position shown in Fig. 10.

A drip board 130 is pivoted at its opposite ends to frame 6 and outer end frame 82 as by stud such as 132 for tilting movements. An ear 134 carried by the yoke 40 co-operates with a curved seat 136 on the end of the drip board so that as the yoke is oscillated between inoperative and operative positions the drip board is tilted from a horizontal position or returned from a tilted position to the horizontal position shown in Fig. 11. When the member 90 is tilted to the left, as shown in Fig. 11, the board 130 is tilted so that water dripping from the rolls or from the clothes being passed therethrough is directed by the member 130 onto one of the members 110. In this way water is directed back into the tub from which the clothes have been withdrawn.

The members 110 not only function as covers for concealing and protecting the rolls but also as drain members for the wringer. As an important feature of the invention, means is provided which tends to return the yoke to neutral position when the upper roll guard unit is unlocked from the receivers. To accomplish this detents, such as 140, are slidably in the opposite sides of yoke 40 (see Fig. 6) which are spring pressed outwardly by means of springs such as 142. The lower ends of the detents, when the 70 75

yoke is in neutral and inoperative positions, yieldingly bear on the upper edges of the connecting plate members 80. When the yoke is swung to either of its operating positions, the 5 detent at the side thereof away from the leading-in side of the rolls tends to return the yoke to neutral position. Then, when the roll unit is released, the detent returns the yoke to its neutral inoperative position.

10 While I have described the invention in great detail and with respect to a preferred form thereof, it is not desired to be limited thereto since many changes and modifications may be made therein without departing from the spirit and 15 scope of the invention. What it is desired to claim and secure by Letters Patent of the United States is:

1. A wringer comprising in combination, a support, a pair of coacting rolls, a pair of cover members pivoted to said support for swinging movements between positions at the sides of the rolls and extended positions below one of said rolls, a pair of guard plates extending along the other of said rolls, pivotal connections between 20 said plates and said support whereby the longitudinal edges of said plates may overlie the edges of said cover members when in position at the sides of the rolls or be disposed adjacent the sides 25 of said roll when the cover members are away therefrom.

2. A wringer comprising in combination, a support, a pair of coating rolls, cover plates at opposite sides of said wringer pivoted to the said support for swinging movements between extended positions below one of said rolls and positions at opposite sides of the rolls, a drip board below the said one roll for directing water onto said cover members when in extended position.

3. A wringer comprising in combination, a support, a roll therein, a roll guard having a roll mounted therein adapted to bear on the first-named roll, cover plates pivoted at opposite sides of said support for swinging movements between outwardly extending positions below one of said rolls and upright positions at opposite sides of said rolls, guard plates extending at opposite sides of the second-named roll and pivoted to said roll guard whereby their lower edges may swing towards and away from said roll, said guard plates being arranged so that their outer marginal edges may overlie said cover plates when said cover plates are in upright position and lie against said second-named roll when said cover plates are in extended position, and releasable locking means associated with said support for releasably locking said cover plates in extended position.

4. A wringer comprising in combination, a support, a roll therein, a roll guard having a roll mounted therein adapted to bear on the first-named roll, cover plates pivoted at opposite sides of said support for swinging movements between outwardly extending positions below one of said rolls and upright positions at opposite sides of said rolls, guard plates extending at opposite sides of the second-named roll and pivoted to said roll guard whereby their lower edges may swing towards and away from said roll, said guard plates being arranged so that their outer marginal edges overlie said cover plates when said cover plates are in upright position and lie against said second-named roll when said cover plates are in extended position, releasable locking means associated with said support for releasably locking said cover plates in extended position, and means associated with said roll guard and guard plates tending to urge the said guard plates in a direction whereby their marginal edges are caused to yieldingly bear on said cover plates when in upright position or said second-named roll when the cover plates are in extended position.

5. In a wringer, spaced side frames, rolls between the side frames, a control bar for the wringer extending above the rolls, drain boards movable from a lowered position projecting from opposite sides of the frames to a raised position closing the space between the frames on opposite sides of the rolls, and plates pivoted on said control bar and extending on opposite sides thereof for closing the space between the upper ends of the drain boards when in the raised position. 35

6. In a wringer, spaced side frames, rolls between the side frames, a control bar for the wringer above the rolls, drain boards movable from a lowered position projecting from opposite sides of the frames to a raised position closing the space between the frames on opposite sides of the rolls, and means carried by said control bar for overlapping the drain boards to hold the drain boards in the raised position. 40

7. In a wringer, spaced side frames, rolls between the side frames, a control bar for the wringer above the rolls, drain boards movable from a lowered position projecting from opposite sides of the frames to a raised position closing the space between the frames on opposite sides of the rolls, and plates pivoted on said control bar and extending on opposite sides thereof for closing the space between the drain boards when in the raised position, said plates co-operating with said drain boards to hold the drain boards in the raised position. 55

JULIAN L. PERKINS,
